UNITED STATES PATENT OFFICE

2,050,409

FIRE AND THEFT ALARM SWITCH

Frank Price Anthony, New Bloomfield, Mo.

Application August 9, 1935, Serial No. 35,531

1 Claim. (Cl. 200—44)

This invention appertains to new and useful improvements in protecting switches for motor vehicles and principally automobiles and the principal object is to provide a novel switch means for cutting off the battery from the various electrical features of the vehicle to the end that a short circuit cannot occur and at the same time providing a safeguard against the theft of the vehicle.

10 During the course of the following specification other important objects and advantages of the invention will become apparent to the reader.

In the drawing

15 Figure 1 represents a longitudinal vertical sectional view through the protector.

Figure 2 represents a horizontal sectional view through the switch.

20 Figure 3 represents a diagrammatic view of the elements of the switch in association with the current supply.

25 Referring to the drawing wherein like numerals designate like forms, it can be seen that numeral 5 represents a casing provided with a removable top 6. In the casing 5 are the grooved retainers 7—7 for supporting the dielectric panel 8. This panel 8 is provided with a pair of contacts 9—9 having on one side thereof, threaded shanks 10 which extend through the panel and are equipped with nuts 11, thus forming binding posts to which the battery lead 12 can be connected and with which the jumper 13 to the distributor is connected.

30 Referring to Figure 1 it can be seen that numeral 14 represents the lock having a bore 15 in the lower portion thereof and the bolt 16 of the lock projectable into this bore. Numeral 17 represents the fixed pin disposed between the side walls of the casing 5 and rockable on this is the dielectric link member 18 arranged in parallel relation with the shank 19 secured at one end between the upper ends of the links 18. The shank 19 has the leaf spring contactor 21 secured thereto and has an extension slidable through the partition 8.

35 40 45 50 The pin 20 is provided at its intermediate point with an opening for receiving the pivot pin 22 extends through the slot 23 at the lower ends of the dielectric links 18 and as can be seen in Figure 1, the elongated control rod 24 provided with a knob 25 at its outer end extends into the casing 5 and is bifurcated at its inner end and perforated to straddle the intermediate portion of

the pin 20 and receive the pivot pin 22. Pin 20 has a stop flange 26 thereon between which and the panel 8 a coiled extensible spring 27 is located.

As can be seen in Figure 1, it will be understood that when the driver is about to enter the automobile, he unlocks the lock 14 by way of a suitable key 28 which retracts the bolt 16 and frees the pin 20 so that the spring 27 forces the pin 20 toward the left in Figure 1.

The leaf spring contactor 21 now bridges the contact 9—9 so that the current can travel from the battery 29 by way of the lead 12 of the switch and the jumper 13 to the electrical features of the vehicle.

When the driver is about to leave his car and wants to guard the same, he forces inwardly on the rod 24 which moves the bolt 20 toward the right in Figure 1 against the action of the spring 27 and results in the bolt 16 engaging into a notch in the rod 20. This action rocks the links 18 and causes removal of the contactor 21 from the contact 9—9. Thus the lead of a battery is broken so that no short circuit can occur in the appliances or electrical features of the vehicle.

Having described the invention, what is claimed as new is:

A switch of the character described comprising a casing provided with a removable closure at one side thereof, a pair of guides in the casing, one at the top and one at the bottom thereof, a dielectric partition in the casing having its upper and lower edges engaged into the slide and being removable with respect thereto, a pair of contacts on the dielectric partition at one side thereof, a binding post at the opposite side of the partition and extending through a connection with the contacts, a rocker of dielectric material mounted in the casing and provided with a hand rod extending through one end of the casing whereby the rocker can be oscillated, said hand rod being pivotally connected to the lower end of the rocker, a guide rod extending from the same end of the rocker and through an opening in the partition and being detachably connected with respect to the rocker, a spring on the rod interposed between the rocker and the partition, a contactor on the upper end of the rocker for engagement with the contacts, a detachable connection between the contactor and the rocker, and a guide rod extending from the contactor and through an opening in the partition.

FRANK PRICE ANTHONY.
